UNITED STATES PATENT OFFICE

159,052

TEMPERATURE CONTROLLING FAUCET

Harold W. Darr, Minneapolis, Minn., assignor to
Cole Valve Company, Duluth, Minn.

Application October 22, 1947, Serial No. 142,081

Term of patent 14 years

(Cl. D4—3)

To all whom it may concern:

Be it known that I, Harold W. Darr, a citizen of the United States, residing at Minneapolis, State of Minnesota, have invented a new, original, and ornamental Design for Temperature Controlling Faucet, of which the following is a specification, reference being had to the accompanying drawing, forming a part thereof.

Figure 1 is a perspective view of a temperature controlling faucet, showing my new design.

Figure 2 is a rear elevational view of the invention.

Figure 3 is a side elevational view of the invention.

Figure 4 is a front elevational view of the invention.

Figure 5 is a top plan view of the invention.

I claim:

The ornamental design for a temperature controlling faucet, as shown.

HAROLD W. DARR.
